UNITED STATES PATENT OFFICE.

HENRY W. PORTER, OF FORESTVILLE, CONNECTICUT, ASSIGNOR TO PETER T. FARRELL AND JOHN M. TOOHEY, OF NEW BRITAIN, CONNECTICUT.

MECHANISM FOR OPERATING INTERMITTINGLY-ROTATING SHAFTS.

SPECIFICATION forming part of Letters Patent No. 634,068, dated October 3, 1899.

Application filed June 21, 1899. Serial No. 721,370. (No model.)

To all whom it may concern:

Be it known that I, HENRY W. PORTER, a citizen of the United States, residing at Forestville, in the county of Hartford and State of Connecticut, have invented certain new and useful Improvements in Mechanism for Operating Intermittingly-Rotating Shafts, of which the following is a specification.

My invention relates to mechanism for operating intermittently-rotating shafts; and the objects of my invention are simplicity in construction and efficiency in operation.

In the accompanying drawings, Figure 1 is a front elevation of my machine, the upper portion of the standards being represented as broken off. Fig. 2 is a side elevation of the same, showing the left-hand end. Fig. 3 is a side elevation as seen from the right, but with the right-hand standard and movement-plate removed in order to better show the other parts. Fig. 4 is a sectional side elevation on the line $\alpha\alpha$, Fig. 1. Fig. 5 is a detached and enlarged side elevation of one of the trip-springs, and Fig. 6 is a detached view of a part of the stop-disk with one of the trip-springs removed in order to show the socket for securing the same to the said stop-disk.

My machine is applicable for use in various mechanisms where an intermittently-rotating shaft is employed. In the form shown it is especially designed for operating intermittently the rotary shaft A of a machine for exhibiting transparencies, the said shaft being provided with heads 77 for carrying the transparencies, which may be arranged in any suitable holder mounted on and carried by the said heads. The side ears or lugs 8 on the said heads are to prevent the holder from working laterally out of place. Any other devices for any desired purpose in connection with an intermittently-rotating shaft may be substituted on the said shaft for the heads 77.

B, Fig. 1, designates a base to which the standards 9 are secured. The tops of the standards may be of any desired shape and extend to any desired height, according to circumstances. For the purposes of my invention it is only necessary that the right-hand standard, as viewed in Fig. 1, shall extend high enough to support the time-train C

and the other high enough to support the spring-motor D, and I have therefore represented said standards as broken off just above these trains.

My machine is especially designed to operate the shaft A. Said shaft is mounted to revolve in suitable bearings on the standards 9, the said bearings on one side being formed directly in the movement-plate 10 of the spring-motor train D and on the other side in the movement-plate 11 of the train C. The standards are centrally and vertically slotted, as at 12, whereby the respective trains or movements C D or other parts may be adjustably secured thereon by means of screws 13 and washers 14; Fig. 2, the said screws passing through the washers and standards and into a nut or threaded hole.

The spring-motor train D may be of any ordinary construction, and any other known driving mechanism that will have a tendency to drive said shaft when released may be substituted therefor as an equivalent. As shown, said motor-train D is composed of a frame, two springs 15, main wheels 16, pinions 17, and wheel 18, that engages with and drives the pinion 19 on the shaft A. The parts of the said wheels and pinions that are hidden by other parts in Fig. 2 are indicated by broken circles in said figure. Rigidly mounted on the opposite end of the shaft A is the stop-disk E, having upon one side a series of stoppins 20 and on its other side a corresponding series of trips 21, pivoted to said disk, as at 22, with their beveled ends projecting therefrom. Said trips are normally forced against their stops 23 by means of the springs 24. These springs are rigidly secured by one end to the stop-disk E in any proper manner. In Figs. 5 and 6 I have illustrated one way of securing said springs to said disk. Each spring is provided at its heel with a lug 25, and the disk is provided with slits or sockets 26, into which the said lugs may be forced with sufficient friction to hold them in place. The rigid ends of the springs are thus secured to the stop-disk, which serve as stops to limit the movement of the trips 21 in one direction on the said disk. I prefer to extend the movement-plate 11 of the fly-wheel motor or time-train C far enough to form the bearing for the

shaft A within it, as shown; but it is only necessary that it shall be fixed relatively to the said movement-plate. The companion movement-plate 27 for the said train C is only large enough to confine the parts belonging specifically to the said train. Upon a post 28 on the plate 11 I mount the angle-lever 29 30, of which 29 is its stopping-arm, and 30 its tripping-arm, the latter being provided with a lateral wing 31, that extends over the edge of the disk E and its trip for engaging the same, as hereinafter described. Rigidly connected with this angle-lever is a tripping-lever 32, the curved upper end of which extends upwardly to the fly-wheel or time-train in position for being acted upon by the trip-pins 33 of the wheel 34 of the said train at regular intervals of time. I call the train C a "time-train," because it is a spring-motor whose motion is retarded or prolonged by a fly-wheel for making the train run slowly for a considerable time and to revolve its wheels at a regular speed, so that one of its wheels 34, carrying trip-pins 33, will revolve in a given predetermined time and act upon the tripping mechanism herein-after described to operate it at regular intervals of time. As shown, said train consists mainly of a frame, two main wheels, and springs 36, and wheels 37 34 39 40, fly-wheel 41, and connecting-pinions, the same being a well-known train and for which other analogous trains may be substituted. The angle-lever 29 30 is provided with a spring 38, which 35 has a constant tendency to force the said lever in a direction to disengage its stopping-arm from the stop-pins 20 of the stop-disk E. The two members of the angle-lever are so related to each other and the stop-disk that 40 when the tripping-arm 30 has its wing 31 in engagement with the edge of said disk the end of the stopping-arm will be carried out of the path of the stop-pins 20, and as soon as the trips act to slightly elevate the said wing 31 from 45 said disk, as shown in Figs. 3 and 4, the said arm will be in the path of the said stop-pins, and consequently will engage one of the said stop-pins and prevent the motor D from driving the shaft A so long as the said arm remains in the path of the said pin. When the 50 time-train is in motion, the wheel 34 revolves slowly, and at each third of a revolution (when the wheel has three trip-pins) one of the trip-pins 33 engages the trip-lever 32 and 55 moves said lever in the direction to lift the tripping-arm 30, so as to lift it over the end of the trip 21 with which it may be engaged. The spring 24 immediately moves said trip out of the way of the wing 31, while the stop-disk is still held by the stop-lever 29 in engagement with one of the stop-pins. Soon 60 after the trip is released the trip-pin 33 passes the downwardly-projecting curved upper end of the trip-lever 32 and releases said lever and 65 connected angle-lever to the force of its spring 38, carrying said levers to the position indicated by broken lines in Fig. 3, the wing 31

of the tripping-arm 30 falling upon the edge of the stop-disk, while the stop-lever disengages the stop-pin 20 to release the stop-disk 70 to the force of the motor D, so that said shaft moves forwardly. The succeeding trip will engage the wing 31 of the tripping-arm 30 and move said trip on its axis in the direction to compress its spring as far as the said spring 75 will permit, and then said trip will force the tripping-arm upwardly and bring the stop-lever into the path of the pins 20, so as to arrest the movement of the stop-disk after it has moved one-sixth of a revolution, this position of the said parts being illustrated in connection with the upper one of the trips in Fig. 4. At the next third of a revolution of the wheel 34 another one of the pins 33 engages the trip-lever 32 and again releases the 80 shaft A to the action of its driving mechanism, permitting it to move another sixth of a revolution, as before described, and so on repeatedly as long as the train is in motion and power is applied to the drive-shaft A a fraction of a revolution every time it is released by the said fly-wheel train. In the particular machine from which the accompanying drawings were made the shaft A moves forward regularly once in every five seconds. Its 85 movement is made in less than one second, so that it remains at rest fully four seconds between each intermittent movement. 90 While I prefer to lift and release the tripping-arm of the angle-lever by the time-train, it is evident that the action of the said tripping-arm relatively to the stop-disk would be the same if the said tripping-arm were lifted and released by other mechanism or by hand. 95 It is apparent that some changes from the specific construction herein disclosed may be made, and therefore I do not wish to be understood as limiting myself to the precise form of construction shown and described, but desire the liberty to make such changes 100 in working my invention as may fairly come within the spirit and scope of the same.

I claim as my invention—

1. The combination of the stop-disk E having a series of stop-pins, with a series of spring-pressed trips pivoted on said disk, the angle-lever 29, 30, for acting on the said pins and trips, and a time-train for controlling the action of the said angle-lever, substantially as described. 115

2. The combination of the shaft A, a motor acting to drive the said shaft when released, a stop-disk having a series of stop-pins, a series of spring-pressed trips pivoted on said disk, the angle-lever for acting on the said pins and trips, a trip-lever, rigidly secured to and extending beyond the reach of the said angle-lever, a spring for pressing the said angle-lever in one direction and a trip-pin wheel revolving at a given speed for acting on the said trip-lever at regular intervals of time, substantially as described. 125

3. The combination of the stop-disk having a series of stop-pins and a series of spring-

pressed trips projecting from its edge, and the angle-lever 29, 30, for engaging the said stop-pins and trips, substantially as described.

4. The combination of the stop-disk having a series of stop-pins, and a series of spring-pressed pivoted trips projecting from the edge of said disk, the angle-lever 29, 30, for engaging the said stop-pins and trips, a spring for forcing the said angle-lever in the direc-

tion to release it from the said stop-pins and to a time-train for operating the said angle-lever at regular intervals of time, substantially as described.

HENRY W. PORTER.
